FIG. 1 is a front perspective view of a wicker saucer lounge chair of my new design;
FIG. 2 is a front elevation view thereof;

FIG. 3 is a left side elevation view thereof, a right side elevation view thereof being a mirror image;

FIG. 4 is a rear elevation view thereof;

FIG. 5 is a top plan view thereof; and,

FIG. 6 is a bottom plan view thereof.

The broken lines in the figures are for the purpose of showing environmental structure and form no part of the claimed design.
